US0D1010083S

(12) **United States Design Patent** (10) **Patent No.:** **US D1,010,083 S**
(45) **Date of Patent:** **** Jan. 2, 2024**

(54) **AIR CONDITIONER**

(71) Applicants: **Takaaki Sanagi**, Osaka (JP);
Kouichirou Seki, Osaka (JP); **Kaichi Tsuji**, Osaka (JP)

(72) Inventors: **Takaaki Sanagi**, Osaka (JP);
Kouichirou Seki, Osaka (JP); **Kaichi Tsuji**, Osaka (JP)

(73) Assignees: **DAIKIN INDUSTRIES, LTD.**, Osaka (JP); **DAIKIN AIRCONDITIONING INDIA PVT. LTD.**, Haryana (IN)

(**) Term: **15 Years**

(21) Appl. No.: **29/809,259**

(22) Filed: **Sep. 27, 2021**

(30) **Foreign Application Priority Data**

Mar. 31, 2021 (IN) 341685-001

(57) **CLAIM**

The ornamental design for an air conditioner, as shown and described.

DESCRIPTION

FIG. 1 is a perspective view of an air conditioner showing our new design;

FIG. 2 is a front view thereof;

FIG. 3 is a rear view thereof;

FIG. 4 is a plan view thereof;

FIG. 5 is a bottom view thereof;

FIG. 6 is a left side view thereof; and,

FIG. 7 is a right side view thereof.

The broken lines shown in the figures are for the purpose of illustrating portions of the air conditioner and form no part of the claimed design.

1 Claim, 6 Drawing Sheets
